(57) **CLAIM**

The ornamental design for a building scaffolding column top sleeve, as shown and described.

DESCRIPTION

FIG. 1 is a perspective view of the building scaffolding column top sleeve, particularly illustrating the building scaffolding column top sleeve installed in a building scaffolding construction;

FIG. 2 is a perspective view of the building scaffolding column top sleeve;

FIG. 3 is a front side view of the building scaffolding column top sleeve of FIG. 2; and,

FIG. 4 is a top view of the building scaffolding column top sleeve of FIG. 2.

The left side view, right side view, and rear side view are identical to the front side view. The bottom view is identical to the top view. The broken lines in the drawings are included for the purpose of illustrating environment and form no part of the claimed design.
